[57] CLAIM

The ornamental design for a desk set, as shown and described.

DESCRIPTION

FIG. 1 is a perspective view showing the front, top and right side of a desk set embodying my new design;

FIG. 2 is a left-side elevational view thereof;

FIG. 3 is a rear elevational view thereof;

FIG. 4 is a bottom plan view thereof;

FIG. 5 is a top, right front perspective view of a second embodiment of my new design;

FIG. 6 is a top, right front perspective view of a third embodiment of my new design; and,

FIG. 7 is a top, right front perspective view of a fourth embodiment of my new design.

The left side, rear and bottom views of the embodiments of FIGS. 5, 6, and 7 are identical to FIGS. 2, 3, and 4 with the exception of the vertical element holder.

FIG. 3

FIG. 2

FIG. 4

FIG. 7
